UNITED STATES PATENT OFFICE.

DANIEL BLYDENBURGH, OF SOUTH ATTLEBORO, MASSACHUSETTS.

CARRIAGE-THREADING DEVICE.

1,338,809.

Specification of Letters Patent. Patented May 4, 1920.

Application filed January 2, 1919. Serial No. 269,181.

To all whom it may concern:

Be it known that I, DANIEL BLYDENBURGH, a citizen of the United States, residing at South Attleboro, county of Bristol, 5 and State of Massachusetts, have invented certain new and useful Improvements in Carriage-Threading Devices, of which the following is a specification.

My invention relates to carriage threading devices, that is, to devices especially adapted for threading the carriages of lace making machines.

A carriage for a lace making machine comprises a thin metal plate of general triangular form and provided with a large circular opening to receive the bobbin and an eye to receive the thread from the bobbin. The bobbin comprises two thin disks spaced slightly apart to receive the thread between them, and is held in place in an aperture in the carriage by means of a flange projecting inwardly from the periphery of the aforementioned aperture for substantially half its circumference, and a spring pressed 20 25 30 35 40 45 50 55 60 65 70 75 80 85 90 95 100 tent substantially diametrically opposite said flange. A lace making machine usually contains several thousands of these carriages, and to insert the freshly filled bobbins and thread the eye of the carriage in the usual manner consumes considerable time. The carriages *per se* form no portion of my invention, but it is necessary to refer to the same and their construction in order to fully understand the device forming the subject matter of the present invention and its operation.

The object of my invention is to provide a simple, manually operable device to facilitate placing the bobbin in the carriage and threading the eye of the carriage. A further object of my invention is to provide a device as mentioned which may be readily adjusted to the convenience of the operator, and also capable of adjustment to effectually 45 50 55 60 65 70 75 80 85 90 95 100 thread the carriages. Other objects will appear hereinafter.

With these objects in view, my invention consists generally in a suitable base, a pivotally mounted table to receive the carriage to be threaded and provided with stops to properly position the carriage thereon, and a hook adapted to pass through the eye of

the carriage when the table is tilted. My invention further consists in a device as mentioned further characterized by such construction as will permit of the hook being adjusted with relation to the table so as to insure the hook passing freely through the carriage eye. My invention further consists in a device as mentioned further characterized by certain depressions in the table whereby the threaded carriage may be readily withdrawn therefrom without danger of cutting or injuring the thread which has been threaded through the carriage eye. My invention further consists in various details of construction and arrangements of parts all as will be fully described herein-after and particularly pointed out in the claims.

My invention will be more readily understood by reference to the accompanying drawings forming a part of this specification, and in which—

Figure 1 is an elevation of a carriage threading device embodying my invention.

Fig. 2 is a plan view of the same.

Fig. 3 is an elevation of the device at substantially right angles to Fig. 1, partially in section.

Fig. 4 is a detail section on substantially the line 4—4 of Fig. 3.

Fig. 5 is a plan view of a carriage of a lace making machine such as is adapted to be threaded by the threading device.

Fig. 6 is a detail section on the line 6—6 of Fig. 5, upon an enlarged scale, and

Fig. 7 is a similar section on the line 7—7 of Fig. 5, also upon an enlarged scale.

Referring now to the drawings, 10 indicates the base of the device, which comprises a cylindrical sleeve 11 and a base flange 12, preferably connected by a flared or conical portion 13. The flange 12 is provided with apertures 14 to receive securing devices for fastening the device to a board or table.

Arranged in the base 10 is a standard 15, fitting snugly within the cylindrical portion 11 but adapted for vertical or rotary adjustment therein, a set screw 16 being provided to hold the same in adjusted position. A head 17 is provided upon the upper end of the standard 15 and provided with a horizontal, longitudinally-disposed bore 18 in

which is slidably mounted an arm 19. 20 indicates a set screw for holding the arm 19 in adjusted position. The arm 19 is provided with a vertically disposed aperture 21 to receive the stem of a hook 22, said hook being held in position by a set screw 23.

Pivots mounted upon the head 17 is a table 24. This is substantially horizontally disposed and provided with a pair of depending ears 25 arranged, one upon each side of the head 17, and pivotally mounted upon a pin 26 extending transversely through the head. 27, 27 indicate cotter pins extending through the pivot pin 26. The ears 25 are each provided with a peripheral aperture 25', the end walls of which form stops to engage a pin 17' on the head 17 to limit the swing of the carriage.

The carriage is substantially triangular in form and is provided with a pair of lugs 28, the adjacent faces of which are angularly disposed to receive the carriage between them, the angular disposition being such as to conform to the sides of the carriage. By this construction the carriage is readily positioned accurately upon the table by merely sliding the same into position of engagement with said lugs. The carriage is formed with a large centrally disposed aperture 29 and with longitudinally disposed depressions or grooves 30 in alignment upon opposite sides of the said aperture, for purposes hereinafter described.

35 The carriage illustrated in Figs. 5, 6 and 7 forms no part of the present invention *per se*, but is illustrated and described in order to get a perfect understanding of the operation of the threading device. 31 indicates

40 the carriage proper which comprises a thin metal plate of a general triangular shape, as shown in Fig. 5, and provided with a central aperture 32 to receive the bobbin 33. The bobbin comprises two plates 34 spaced apart to receive the thread 35 between them. Projecting inwardly from substantially one-half the circumference of the aperture 32 is a flange 36 formed by reducing the thickness of the carriage plate,

45 and adapted to be received between the edges of the plates 34 of the bobbin. Substantially diametrically opposed to the flange 34 is a spring-pressed detent 37 which also engages between the plates 34, said detent and flange 36 serving to hold the bobbin in the carriage. 38 indicates the eye of the carriage and 39 a groove extending substantially tangentially to the periphery of the bobbin and through which the

50 thread passes from the bobbin to the eye beneath the plane of the surface of the carriage. As above stated, the primary object of the present invention is to provide a device to facilitate placing a newly filled bobbin 33 within the carriage 31 and to thread

the thread from the bobbin through the eye 38 of the carriage.

The operation of the device is as follows: An empty carriage is placed upon the table 24 and slid into position, that is, until its sides firmly engage the lugs 28. A bobbin 34 is then placed within the aperture 32 of the carriage and moved by the operator until the flange 36 engages between the edges of the plates 34. This is readily accomplished as access is given to the under side of the bobbin through the aperture 29 in the table. The portion of the carriage and bobbin containing the spring detent projects beyond the table, as illustrated in dotted lines in Fig. 2, so that the said detent may be readily positioned after the bobbin has been positioned within the carriage. The operator then, holding the carriage firmly on the table with one hand and the end of the thread in the other hand, rocks the table until the hook 22 passes through the eye 38 of the carriage; then engages the thread under said hook and returns the carriage to normal position, the hook drawing the thread through the eye. The carriage is then removed by drawing the same backwardly from the lugs 28, the depression 30 being provided to prevent the table from cutting or injuring the thread projecting from the bobbin side of the carriage during the removal of the same from the table. It is obvious that the idea of angular position of the table may be regulated to suit the convenience of the operator and held in adjusted position by means of the screw 16, and also that the hook 22 may be readily positioned to properly enter the eye by means of the construction described.

I claim:—

1. A device of the class described comprising a fixed hook, a pivotally mounted table, and means on said table for positioning the carriage thereon, substantially as described.

2. A device as set forth in claim 1 further characterized by means for limiting the swing of the table.

3. A device as set forth in claim 1 further characterized by a longitudinally disposed thread-receiving depression therein.

4. A device of the class described comprising a supporting member, a table pivotally mounted thereon, an arm longitudinally adjustable beneath said table, a vertically disposed needle supported by said arm, and means for positioning a carriage on said table, substantially as described.

5. A device as set forth in claim 4 further characterized by means for adjusting said needle vertically.

6. A device of the class described comprising a base, a standard mounted therein for vertical and rotary adjustment, a head on said standard, a table pivotally mounted

on said head, a needle supported by said head, and means for positioning a carriage on said table, substantially as described.

7. A device as set forth in claim 6 further characterized by means for adjusting said needle with relation to said table, substantially as described.

In testimony whereof I have signed my name to this specification in the presence of two subscribing witnesses.

DANIEL BLYDENBURG.
